ADJUSTABLE SASH HOLDER

Charles F. Recklitis, Mahanoy City, Pa.

Application April 4, 1947, Serial No. 739,320

2 Claims. (Cl. 292—74)

1

This invention relates to adjustable sash holders intended to be employed in frictionally holding dwelling windows in any position to which moved.

The problem of replacing broken sash cords is a common and troublesome one involving considerable expense and often marring of the window construction. The sash holder of the present invention may be used as a substitute for sash balancing means which have become broken, or it may be installed in new windows with an appreciable saving in construction costs.

It is the general object of this invention to provide a simple and efficient form of friction engaging sash holder which may be conveniently adjusted at any time to provide the required amount of resistance to window movement.

In particular, it is an object of this invention to provide a sash holder having a spring pressed member for frictionally engaging the window frame adjacent the edges of the sash which may be very easily and readily installed. A related object is attained by the provision of an adjustable sash holder comprising a minimum of parts.

It is a further object of this invention to provide a sash holder having an unsymmetrical configuration which will afford a relatively larger amount of clearance with respect to the glass of the sash and thereby minimize the possibility of breakage in installation or adjustment.

These and other objects of the invention will be apparent from a consideration of the following detailed description of a preferred embodiment of the invention taken with the accompanying drawings in which:

Fig. 1 is a front elevation of a conventional window structure partially sectioned to show the application of the sash holder of this invention;

Fig. 2 is an enlarged fragmentary section taken on line II—II of Fig. 1 showing the sash holder in operative position; and

Fig. 3 is an exploded perspective view showing further details of the sash holder.

With reference to Figs. 1 and 2, a conventional window structure 10 is shown comprising a window frame 12, an upper sash 14, and a lower sash 16. The lower sash 16 includes stiles 18 and 20 maintained between a parting strip 22 and an inside stop strip 24 in the conventional manner indicated in Fig. 2.

Preferably, the upper and lower sashes 14 and 16 will each be provided with two sash holders 26 mounted in opposed relation in opposite stiles. The construction of the sash holder is such that

two holders are often sufficient for a single sash, although additional ones may be used where the sash is unusually large or heavy. If only a single sash holder is employed, there may be a tendency to force the sash to one side of the frame and produce unwanted friction between the sash and the adjacent side of the frame.

The details of construction and the arrangement of the parts of the sash holder 26 are best illustrated in Fig. 3. The sash holder 26 is preferably made of a non-corroding metal and formed to shape in any conventional manner. Frictional engagement with the window frame 12 is attained by a rectangular runner block 28 received in a chambered housing member 30 which is fitted into the stile 18 in the manner shown best in Fig. 2, and urged into engagement by a spring 32 having an adjusting screw 34.

The runner block 28 is elongated to provide adequate bearing surface with the window frame and to maintain the window sashes in parallel relation thereto. By forming the block 28 with opposite rounded ends 36, 36, gouging of the window frame is prevented. It will be noted that the runner block 28 includes a plunger portion 38 provided with an end 42 of reduced diameter forming an abutment shoulder 40 for engagement with the adjacent end of the spring 32.

The chambered housing member 30 is of integral construction formed to provide a rectangular slot 45, a trough portion 46 forming a continuation of the opposite sides of the slot 45, and a tubular portion 48. The free end of the tubular portion 48 is provided with internal threads 50 for threaded engagement with the adjusting screw 34.

It is to be particularly noted that the slot 45, which extends lengthwise of the elongated face plate portion 43, is offset with respect to the longitudinal axis of that portion. This unsymmetrical arrangement of the slot 45 and the trough portion 46 which forms an in line continuation thereof is an important feature of the invention. The tubular portion 48, which is preferably circular in cross-section, opens into the bottom of the trough portion 46, is disposed centrally thereof, and has an internal diameter approximately that of the width of said trough portion.

The complementary engagement of the face plate 43 and trough portions of the housing 30 with the rectangular runner block 28 constrain the latter from turning and together with the close fitting plunger 38 guide its outward and inward reciprocating movement.

In the installation of one of the sash holders 26, the stile 18 as shown in Fig. 2 is mortised to provide a recess 52 for the face plate 43 and trough portions and bored to provide an opening accessible at the inner edge of the stile for receiving the tubular portion 48 and permitting adjustment of the screw 34. The housing 30 will extend lengthwise of the stile in the manner shown in Fig. 1 and will have its face plate portion 43 turned so that the offset of the slot 45 will be in the direction of the inside of the sash 16, that is toward the stop strip 24. In this manner the necessary width of the face plate 43 is attained while at the same time, the bored opening and the adjusting screw 34 are given added clearance with respect to the plane of a window glass 56, for example.

One end of the coiled compression spring 32 encircles the reduced end 42 and abuts the shoulder 40 of the plunger 38. Rotation of the kerfed adjusting screw 34 in the proper direction will increase or decrease the resilient force which the block 28 exerts as it slides in the window frame and accommodates itself to any irregularities.

From the preceding detailed description of the preferred embodiment of this invention and its manner of use, it will now be understood that there has been provided an improved form of adjustable sash holder, which is dependable in operation, easy to manufacture and install, and which minimizes the possibility of window breakage during installation or adjustment.

It will be appreciated that the disclosed embodiment is an illustrative one and that changes may be made in the details of construction and arrangement of parts without departing from the spirit of the invention as defined in the appended claims.

Having thus described my invention, what I claim as novel and desire to secure by Letters Patent of the United States is:

1. A sash holder comprising a chambered member adapted to be set into a sash, said chambered member including an elongated face plate having a rectangular slot extending lengthwise thereof, a trough portion forming an inward continuation of the longitudinal edges of said slot, and a tubular portion opening into the bot-

tom of the trough portion centrally thereof; a rectangular runner block complementally fitting the slot and trough portion of the chambered member and having a plunger portion formed and arranged for guided reciprocation in the tubular portion, said plunger being provided with a free end portion of reduced diameter forming with the unreduced plunger portion an abutment shoulder; a coiled spring within the tubular portion encircling the end portion of reduced diameter and having one end arranged to engage the abutment shoulder; and an adjustment screw threaded into the tubular portion to provide an abutment for the other end of the spring.

2. An adjustable sash holder comprising a chambered member adapted to be set into a sash, said chambered member including a rectangular face plate having a rectangular slot extending lengthwise thereof and disposed unsymmetrically with respect to the longitudinal axis of said plate, a trough portion forming an inward continuation of the longitudinal edges of said slot, and a tubular portion opening into the bottom of the trough portion centrally thereof; a rectangular runner block complementally fitting the slot and trough portion of the chambered member and having a plunger portion formed and arranged for close fitting reciprocation in the tubular portion, said plunger being provided with an end of reduced diameter forming an abutment shoulder with said plunger; a coiled spring within the tubular portion encircling the end of reduced diameter and having one end arranged to engage the abutment shoulder; and a screw threaded into the tubular portion to provide an abutment for the other end of the spring.

CHARLES F. RECKLITIS.
